Blanche Yurka Inventor

By her attorney Edward S. Beach -

UNITED STATES PATENT OFFICE.

BLANCHE YURKA, OF NEW YORK, N. Y.

BRASSIÈRE.

Application filed February 23, 1921. Serial No. 447,354.

To all whom it may concern:

Be it known that I, BLANCHE YURKA, a citizen of the United States, and a resident of New York city, in the county of New York and State of New York, have invented a certain new and useful Improvement in Brassières, of which the following is a specification.

This invention relates to brassières. Its objects are to make such wearing apparel in such wise as to be free of all protuberances that can bear injuriously or uncomfortably against the breasts and body portions adjacent thereto, as well as against the rest of the body in its encirclement by the brassière; and also to make the body member of the brassière of a material which if moistened, either artificially or by perspiration, will so slightly adhere to the body that unsightly and uncomfortable shoulder straps will not be required to keep the brassière from slipping down, and that back tapes for securing the ends of the brassière in position will serve to hold the brassière ends in place without drawing the tapes so tightly in place that the upper and under edges of the brassière across the front of the body will be strained against the skin and thereby retard circulation and uncomfortably depress and reddens the skin along such edges; and which when worn will flex with all the movements of the body and also permit the upper back tapes to be pulled downwardly to about the line of the under back tapes for holding the upper corner margins, outwardly of each breast, sufficiently below the arm-pits to permit a low cut gown to be worn without showing the upper corner portions of the brassière under the arms.

In the accompanying drawings forming a part hereof and illustrating my invention,

Fig. 1 is a plan view of the front or outward side of my brassière.

Fig. 2 is a sectional detail thereof at line 45 2—2 of Fig. 1.

Fig. 3 is a front view of a torso, in dotted lines, with the brassière in place.

Fig. 4 is a back view of a torso, in dotted lines, with the brassière in place.

Fig. 5 is a perspective view of a torso, in dotted lines, and of the brassière in a position of wear and shows the under back tapes in normal position with the upper back tapes depressed for lowering the upper corner portions of the body member of the brassière below the arms.

In the drawings, the thin sheet-rubber body member 1 of the brassière is of rectangular shape with cut edges that are not seamed or folded, and are therefore free of protuberances. This body member is freely flexible in all directions and has superposed on the front surface of each of its corner portions, a flattened end portion 2 of a back tape, the two under corner tapes having their extensions indicated by 3, and the two upper corner tapes having their extensions indicated by 4. Over each end portion 2 of a tape, a stay-piece 5 of thin rubber is located; and each flat end portion of a tape is vulcanized on one surface to a corner portion of the body member, each stay-piece 5 being in part vulcanized to the other surface of the end portion of the tape and otherwise marginally vulcanized to the front surface of the body member 1 outwardly of the three edges of the tape between the body member 1 and a stay-piece. The four slight corner protuberances thus formed are on the outward side of the brassière and do not come in contact with the body. The tapes are preferably tied rather than buckled at the spine. By slightly moistening the under surface of the body member 1 before it is put on, the body member will stay in place by slight but sufficient adhesion to the body and the same result will result when the body perspires. Thus shoulder straps are wholly unnecessary for keeping the brassière in place even though the tapes are but gently and not tightly tied together at the back. When the brassière is to be worn with a low cut waist, the tied, upper back tapes may be pulled downwardly to the level of the under tapes; thereby pulling down the upper corners of the body portion 1 downwardly under the arms, as shown in Fig. 5. In such position the ends of the body member will be wrinkled as at 6, under the arms, but such wrinkling will be unobjectionable because of the thinness of the body member. By vulcanizing the tape ends in place between the body member corner portions and the stay-pieces, the tapes are securely anchored to the body member. While it is possible to stitch the tape ends to the corner portions of the body member, the stitches are apt to tear out of the thin rubber. The thin rubber body forming member of the brassière may be of any desired color more or less to match skin coloration or otherwise; and the brassière has the further advantages of maximum

compactness and of not involving the use of any metallic parts unless desired.

What I claim is:

As a new article of manufacture, a brassiere having a thin, oblong, freely flexible sheet rubber body member that is freely elastic in all directions, free from substantial protuberances on its inward, breast-contacting portions and also between such portions, and of a continuous width and length sufficient to cover both breasts and the intermediate body portion; and having upper and under backwardly extending tapes each having a flat end portion flatwise anchored to a corner surface of the body member with a

sheet rubber stay-piece anchored to such flat end portion of the tape and an adjacent corner portion of the body member, the anchorages of the tape ends to the corners of the body member permitting each marginal portion thereof between two tape ends to be freely extensible across the front of the wearer's body, and the free ends of the tapes being adapted to be connected at the back of the wearer's body. 20 25

Signed at New York city, in the county of New York and State of New York, this 9th day of February A. D. 1921.

BLANCHE YURKA.
